UNITED STATES PATENT OFFICE.

MICHAEL McCANN, OF GLENMORRIS, NEW YORK, ASSIGNOR TO FREDERICK OSANN COMPANY, OF NEW YORK, N. Y., A CORPORATION OF NEW YORK.

PULL-OFF MECHANISM FOR BUTTONHOLE-SEWING MACHINES.

Application filed August 5, 1922. Serial No. 579,794.

To all whom it may concern:

Be it known that I, MICHAEL McCANN, a citizen of the United States of America, residing in Glenmorris, Long Island, in the 5 county of Queens and State of New York, have invented certain new and useful Improvements in Pull-Off Mechanism for Buttonhole-Sewing Machines, of which the following is a true and exact description, reference being had to the accompanying drawings, which form a part thereof.

My invention relates to buttonhole sewing machines and particularly to the button hole sewing machines constructed in accordance with my co-pending applications 15 for Letters Patent, Serial No. 325,710 filed 23 September 1919, and Serial No. 566,784, filed 8 June 1922, in which said pending applications the pull off mechanism which 20 forms the subject matter of my present application is shown in two different modifications but not covered by the claims of either application. The object of my present invention is to provide mechanism for actuating a pull off by means of which the 25 pulling off of the thread will be accurately timed in relation to the operations performed by the machine in the completion of the button hole, that is to say, my improved mechanism insures, in the first place, 30 that the pull off shall occur in proper relation to the stopping of the machine; in the second place, that it shall occur in proper relation to the cutting off of the threads 35 at the completion of the button hole; and, in the third place, that it shall occur in properly timed relationship to the cutting of the button hole.

The nature of my improvements will be 40 best understood as described in connection with the drawings which illustrate the machine shown in my two said pending applications, and in which—

Figure 1 is a side elevation of the machine with the housing which encloses the lower part of the machine cut away so as to display the enclosed mechanism and the side plates of the housings enclosing the upper part of the machine removed.

Figure 2 is a top view of the upper arm of the machine, showing the tension device

and pull off supported upon the upper part of the machine.

Figure 3 is a plan view taken as on the section line 3—3 of Fig. 1. 55

Figure 4 is a sectional elevation on the line 4—4 of Fig. 1.

Figure 5 is a sectional elevation on the line 5—5 of Fig. 1.

Figure 6 is a plan view generally similar 60 to Fig. 3, but showing the parts in the position they occupy immediately after the cutter actuating clutch is engaged.

Figure 7 is a side elevation taken substantially on the same line as Fig. 5, but 65 showing the change in the position of certain of the parts which occurs when the cutter actuating clutch is engaged.

Figure 8 is a view generally similar to that of Fig. 7, but showing the parts in the 70 position they occupy when the cutter is operated.

Figure 9 is a plan view showing the position of the parts immediately after the 75 operation of the cutter.

Figure 10 is a similar view showing the position of the parts at the time that the pull off is actuated and immediately before the stopping of the machine.

Figure 11 is a similar view showing the 80 position of the parts after the stop shaft has been partly moved toward the left but has not yet been quite drawn to the position where the machine is again started in operation. 85

Figure 12 is a side elevation showing the belt shifting device and the bar to which the stop finger is attached.

Figure 13 is a detail side elevation showing the pivot bar and actuating cam by 90 means of which the pull off is raised.

Figure 14 is a side elevation of the lever used for shifting the stop shaft.

Figure 15, a perspective view of a portion of the pull off mechanism, and 95

Figure 16, a perspective view of the co-acting portion of the pull off device.

A indicates the housing of the lower part of the machine; A' the vertical arm; A² the horizontal arm, and A³ the head at the end 100 of the horizontal arm. B is an opening formed through the top of the housing A.

2
 C and C', cross ribs extending down from the top of the housing A. D is the main driving shaft of the machine and to the end extending through the housing is secured by any convenient means the disc D² having, as shown, a hard steel wearing face D² and a stop recess indicated at D⁴. D⁵ is a pulley fixed to the disc D², and D⁶ a pulley running loosely on the end of the shaft D. D⁷ is an eccentric secured on the shaft D and connected by means of the eccentric rod E and lever E' to the shaft E² which, through connecting mechanism indicated at E³, gives a reciprocating movement to the needle bar E⁴ guided in the oscillating guideway G² and carrying the needles indicated at E⁵. D⁸ is a gear wheel secured on the shaft D and operating as will be described. D⁹ is a cam secured on the shaft D through its hub D¹⁰. D¹¹ is an eccentric mechanism by which motion is given to the connecting rod I', and D¹² is still another cam secured on the shaft D.

The gear wheel D⁸ drives, through a gear wheel F, a shaft indicated at F', having secured to its end a cam F².

G is a shaft secured in bearings in the upper arm of the machine and having at its left hand end an arm G' which supports the guide G² in which the needle bar moves. To the right hand end of the shaft G is secured the lever G³ having a curved lower end indicated at G⁴, see Fig. 4, and a guide slot formed in it, as indicated at G⁵. Through this curved lower end G⁴ and a guide block secured therein the lever G³ is connected with the lever H secured to the shaft H' which, at its left hand end, carries a lever H² connected so as to actuate longitudinally a shaft H³ to which are secured the loopers, such shaft and loopers being, by the mechanism described, caused to oscillate in synchronism with the necessary needles. The necessary angular oscillation of the shaft H³ is imparted to it through mechanism partly indicated at H⁵, but not shown in detail, as it forms no part of my present invention.

I is a shaft to which an intermittent rotary motion is imparted by mechanism actuated by the shaft D. In this case, eccentric mechanism D¹¹, through an eccentric rod I' and clutch I², engages and actuates the shaft I through the cam I⁴, I⁵ indicating a clutch on the other side of the said cam I⁴ by which it may be actuated by hand. The particular mechanism employed is not fully illustrated for the reason that it forms no part of my present invention. I⁶ is a cam secured to the shaft I, and I⁶ another cam secured to the same shaft. To the face of the cam I⁶ is adjustably attached, as is clearly shown in Fig. 5, finger I' and in the opposite face of the disc is formed the cam recess indicated at I⁸.

J is a slide lever pivoted at one end and operatively engaged by the cam I⁴, as shown in Figs. 1 and 3, the slide block J' moving in the lever J is connected to actuate the feed mechanism indicated partially at J². 70

K is a lever pivoted at K' and actuated through a cam roller K² by the cam I⁶ as best shown in Fig. 4. To the free end of the lever K is connected the rod K³ through which motion is imparted to the pivot lever K⁴, the connection between the said lever and the rod K³ being through a slot indicated at K⁵, the lever K⁴ being pivoted at K⁶, as indicated in Fig. 4. The free end of this lever carries pivotally attached to it, as indicated at K⁷, two slide blocks, one moving in the slot G⁵ of the lever G³ and the other moving in a similar guideway in the oscillating block F³, having a forked lower end F⁴ by which it is engaged and actuated by the cam F² and pivotally supported at F⁶, see Fig. 1. 80 85

L is the cutter actuating shaft secured in the upper horizontal arm of the machine connected, as indicated at L', with a knife carrying bar L², L³, indicating the knife. To the shaft L is secured the lever arm L⁴ carrying the pin L⁵ through which and a link L⁶, slidably connected with the pin, connection is made with the pin L⁷ attached to a sliding clutch member L⁸ supported on the shaft E² and engageable with a fixed clutch member L⁹ attached to such shaft. 90 95

Referring now to the lower part of the machine, M is a longitudinally movable shaft and to the end of this shaft, which projects through the right hand end of the casing A, is secured the forked arm M', one arm of which extends on the side of the hub D', and one arm of which carries the stop finger indicated at M². Also secured to this end of the shaft is the belt shifter indicated at M³ arranged to engage and shift the belt indicated at m³. M⁴, M⁵ are buffers secured to the shaft M and form limit stops to its motion in both directions. To the left hand end of the shaft M is secured the arm M⁶ carrying at its end the knife M⁷ which cuts the threads below the work when the shaft completes its full longitudinal movement toward the right. M⁸ is a spring normally tending to move the shaft M toward the right and at M⁹ I have indicated the usual crank attachment by which the shaft is shifted toward the left on the starting of the machine. Pivoted on the shaft M is the arm N, from the upper side of which projects the latching pin N' and which carries on its free end the plate indicated at N², which plate is notched at the end, as indicated at N³, see Fig. 10. N⁴ is a bracket secured to this shaft and extending beneath the arm N, and N⁵ is a spring supported on this bracket and tending to push the arm N upward. O is a pivot pin 110 115 120 125 130 135 140 145 150 155 160 165 170 175 180 185 190 195 200

secured to the top of the housing A and on which is pivotally supported the latch O' preferably made, as shown, in the form of a bell crank lever with the spring O² acting to turn it in a direction against the pin N'.

P is a lever pivoted in the upright A' at P' and having a forked upper end P² which engages the movable clutch member L⁸. P³ is a pin engaging perforation formed in the lever P, the lower end of which lever is slotted, as indicated at P⁴, to form a guide-way for a sliding plate, to be described, and to this lower end of the lever is secured the pin P⁵ lying in operative relationship to the cam disc I⁵. P⁶ is a sliding plate connected at its upper end to the pin L⁹ on the arm L⁴ and sliding up and down in the guide-way formed between the ends P⁴ of the lever P, the lower end P⁷ of this bar when it is moved out to its lowermost position, extending beyond the end of the lever P. P¹¹ is a spring which normally presses the upper end of the lever P towards the left.

P⁸ is an arm secured to the right hand end of the shaft L and carrying at its end the tubular guide indicated at P⁸ in the face of which is located a spring P⁹ acting to push outward a pin indicated at P¹⁰, this pin being located so that, in the retracted position of the knife actuated by the shaft L and when the lever P is in the position shown in Fig. 1, the pin will engage in the hole P^a.

Q is a bar hinged on the shaft M and carrying on its free end, a plate Q' with an angularly extending end indicated at Q² which extends beneath the pull off rod indicated at Q⁴. This rod is made adjustable in length, as by an adjusting sleeve indicated at Q⁵, Fig. 1, and is normally pressed downward by a spring Q⁶. To the top of the rod Q is secured a thread engaging loop indicated at Q⁷, and below this loop is secured a guide bar indicated at Q⁸. The coacting pull off mechanism is best illustrated in Figs. 1 and 15, consisting of a clip q secured to the top of the machine, formed with downwardly extending hooks q', q', etc. divided by slots indicated at q², the guide pin Q⁸ extending into the slot q² so as to keep Q⁷ in proper relationship to the hooks q'. The threads indicated at q³ pass through the loop Q⁷ and under the hook q'. The plate Q is normally supported by an adjusting screw Q¹² working in a bracket Q⁹ secured to the shaft M and is drawn downward against this adjusting screw by means of a downwardly extending pin Q¹⁰ and the spring Q¹¹ acting on the end of this pin, see Fig. 13.

In Figs. 1 and 3, I have shown at R a lever pivoted at R' having secured to it a pin R² which extends into the groove of the cam D¹². Pivoted on the free end of this lever at R³ is the slide R⁴, moving in a guide mechanism indicated at R⁵ and carrying a

hook R⁶ at its end. This mechanism, while a part of the machine to which my invention is applied, forms no part of my present invention and is, therefore, not shown in further detail.

I have shown at S and S' ordinary tension devices for the threads, and at T, best shown in Fig. 1, I have indicated a longitudinally movable rod with a push button T² at its left hand end and with its right hand end T' engaged with the upper end of the lever P. This rod is normally pushed toward the left by a spring indicated at T³ but when pushed toward the right will push the lever P toward the right and disengage the clutch.

In normally operative position, that is, during the sewing of the button hole, the various parts of the machine are in the position shown in Figs. 1, 3, 5 and 13. Just before the stitching of the button hole is completed, the finger I⁷, on the cam disc I⁵, comes in contact with the plate N² of the locking bar N and presses it downward to the position shown in Fig. 7, in which position it clears the ends P⁴ of the lever P which have previously been resting against its edge, as shown in Figs. 3 and 5, with the result that the spring P¹¹ pushes the upper end of the lever P toward the left, carrying with it the movable clutch member L⁸ which engages the fixed clutch member L⁹. The lower forked end of the lever P now extends over the plate N². The engagement of the clutch members, through the described mechanism connected with the movable clutch member, imparts motion to the cutter shaft L and forces the cutter L³ down through the goods to cut the button hole, and, as the shaft L moves to actuate the cutter, the downward motion of the connected pin L⁵ forces downward the plate P⁶, the end P⁷ of which presses the plate N² further downward, as shown in Fig. 8, carrying the latching pin N' from the position shown in Fig. 7, in which it is still engaged with the latch O', to the position shown in Fig. 8, in which it is disengaged from the latch, permitting the stop shaft M to move under the influence of its spring M⁸ toward the right. This motion of the shaft, however, is arrested by the contact of the plate Q' with the face of the cam D⁹ which results in the parts being brought to rest in the position shown in Fig. 9, in which they are held until the cam D⁹ in its rotation passes below the edge of the plate Q' whereupon the stop shaft and parts connected with it will again move toward the right, carrying the plate Q' over the top of the cam D⁹ and permitting the stop finger M² to contact with the friction surface D³ on the disc D² and finally enter the stop recess D⁴ and arrest the motion of the machine simultaneously with the shifting of the belt M³ to the loose pulley, the final po-

sition of the parts at the time the machine is stopped being shown in plan in Fig. 10, in which figure it will be observed the plate N^2 has passed from beneath the ends P^4 of the lever P on clearing which it will, of course, move upward under the influence of the spring N^5 to its normal level in which its latching pin N' will be in position to be engaged by the latch O' .

10 The upward movement imparted to the plate Q by the cam D^6 is, through its extension Q^2 , imparted to the pull off rod Q^4 which, through the pull off mechanism described, effects a pull off of the threads in 15 nicely timed relation to the operation of the button hole cutter and of the thread cutter and, of course, in very nicely timed relation to the final action of the stop motion described in arresting the motion of the machine. It will be understood that the action 20 of the stop mechanism in arresting the motion of the machine is timed to occur just after the cutter L^3 , after cutting the button hole, has again returned to its uppermost 25 and normal position of rest, in which the pin P^{10} carried by the arm P^8 attached to the shaft L is in alignment with the perforation P^9 in the lever P .

When it is desired to start the machine, 30 the shaft M is drawn toward the left by the treadle lever M^9 , the parts being shown in intermediate position during this movement of the stop shaft in Fig. 11. This motion of the stop shaft, of course, withdraws the 35 stop finger M^2 from the stop recess D^4 and carries with it the pivot arm N and attached plate N^2 which contacts with the lower ends P^4 of the lever P , drawing the pin P^6 out of the recess I^8 in cam disc I^5 40 and, of course, turning the upper end of the lever P toward the right, tends to draw the movable clutch member L^8 out of engagement with the clutch member L^9 . This movement of the lever P also effects the entrance of the pin P^{10} into the hole P^3 , the result of which is to lock the shaft L in 45 the position in which the cutter is in its uppermost position. The movement of the stop shaft also, of course, carries the plate 50 Q toward the left until it clears the cam D^6 and assumes its normal position of rest, as shown in Fig. 13. As shown in Fig. 11, the left hand motion of the shaft M through pin N' presses the latch lever O' outward 55 until on the completion of the motion of the shaft M the latch engages the pin, as shown in Fig. 3, and all of the operative parts are located in the position they occupy during the sewing of the button hole 60 and until the finishing of the button hole cycle of operations described again occurs.

Having now described my invention, what I claim as new and desire to secure by Letters Patent, is:

65 1. In a button hole sewing machine hav-

ing means for stopping the machine as the button hole is finished, comprising and actuated by a longitudinally movable shaft and a spring acting to move the shaft in a direction to actuate the stop mechanism, the combination with said shaft of a latch normally holding it in inoperative position, means acting to release said latch as the button hole nears completion, a bar pivoted on the stop shaft and moving with it, said bar having a pull off actuating extension, a rotating cam actuated by the driving shaft and located to register with and actuate the pivoted bar when the stop motion shaft is released from its latch, and a pull off device arranged to be actuated by the bar extension aforesaid.

2. In a button hole sewing machine having means for stopping the machine as the button hole is finished, comprising and actuated by a longitudinally movable shaft and a spring acting to move the shaft in a direction to actuate the stop mechanism, the combination with said shaft of a latch normally holding it in inoperative position, means acting to release said latch as the button hole nears completion, a bar pivoted on the stop shaft and moving with it, said bar having a pull off actuating extension, a rotating cam actuated by the driving shaft, said cam being located and shaped as described and so that when the stop shaft is released the pivoted bar will first come in contact with the side of said cam and arrest the movement of the stop shaft and then pass over and be engaged by the face of said cam so as to be lifted as the stop shaft completes its motion to stop the machine and a pull off device arranged to be actuated by the bar extension aforesaid.

3. In a button hole sewing machine having means for stopping the machine as the button hole is finished comprising and actuated by a longitudinally movable shaft and a spring acting to move the shaft in a direction to actuate the stop mechanism, a latch for holding the shaft in inoperative position, a button hole cutter, means for actuating said cutter operating as the button hole nears completion, means for releasing the latch moving with the cutter, a bar pivoted on the stop shaft and moving with it, said bar having a pull off actuating extension, a rotating cam actuated by the driving shaft and located to register with and actuate the pivoted bar when the stop motion shaft is released from its latch, and a pull off device arranged to be actuated by the bar extension aforesaid.

4. In a button hole sewing machine having means for stopping the machine as the button hole is finished comprising and actuated by a longitudinally movable shaft and a spring acting to move the shaft in a direction to actuate the stop mechanism, a

- latch for holding the shaft in inoperative position, a button hole cutter, means for actuating said cutter operating as the button hole nears completion, means for releasing the latch moving with the cutter, a bar pivoted on the stop shaft and moving with it said bar having a pull off actuating extension, a rotating cam actuated by the driving shaft, said cam being located and shaped as described and so that when the stop shaft is released the pivoted bar will first come in contact with the side of said cam and arrest the movement of the stop shaft and then pass over and be engaged by the face of said cam so as to be lifted as the stop shaft completes its motion to stop the machine, and a pull off device arranged to be actuated by the bar extension aforesaid.
5. In a button hole sewing machine having means for stopping the machine as the button hole is finished, comprising a friction disc with a stop recess secured to the driving shaft, a spring actuated longitudinally movable stop shaft having a stop finger positioned to contact with the friction disc and enter the recess when the shaft is released and a latch normally holding said shaft in retracted position, the combination therewith of a thread cutter moving with the stop shaft and acting to cut the thread when the stop finger enters the stop recess in the disc, means for releasing the shaft latch as the button hole nears completion, a bar pivoted on the stop shaft and moving with it having a pull off actuating extension, a cam actuated by the driving shaft and located to register with and actuate the pivoted bar when the stop shaft is released from its latch, and a pull off device arranged to be actuated by the bar extension aforesaid.
6. In a button hole sewing machine having means for stopping the machine as the button hole is finished, comprising a friction disc with a stop recess secured to the driving shaft, a spring actuated longitudinally movable stop shaft having a stop finger positioned to contact with the friction disc and enter the recess when the shaft is released and a latch normally holding said shaft in retracted position, the combination therewith of a thread cutter moving with the stop shaft and acting to cut the thread when the stop finger enters the stop recess in the disc, a button hole cutter, means for operating said cutter as the button hole nears completion, means for releasing the latch moving with the cutter, a bar pivoted on the stop shaft and moving with it having a pull off actuating extension, a cam actuated by the driving shaft and located to register with and actuate the pivoted bar when the stop shaft is released from its latch, and a pull off device arranged to be actuated by the bar extension aforesaid.

MICHAEL McCANN.
